UNITED STATES PATENT OFFICE.

JOHN H. FELDERMAN, OF BELLEVUE, IOWA.

FEEDER FOR GRAIN-MILLS.

No. 867,490.

Specification of Letters Patent.

Patented Oct. 1, 1907.

Application filed August 7, 1905. Serial No. 273,086.

To all whom it may concern:

Be it known that I, JOHN H. FELDERMAN, a citizen of the United States, residing at Bellevue, in the county of Jackson and State of Iowa, have invented 5 certain new and useful Improvements in Feeders for Grain-Mills, of which the following is a specification.

My invention relates to feeders for grain mills, and consists in adjustable means for feeding the grain evenly and for preventing stone, pieces of metal and 10 other foreign substances from entering the mill.

The following specification and accompanying drawings, will point out in detail the mode of construction whereby my objects are obtained.

Figure 1, is a side elevation of the device attached to a 15 grinding mill, Fig. 2, is an enlarged sectional fragmentary view of the invention, Fig. 3, is an end view in elevation of the same, and Fig. 4, is a top plan fragmentary view, parts being shown in section.

Referring to the drawings, 2 designates the inclosure 20 or external parts of a grinding mill, 4 the hopper, 5 the wheel attached to the grinding shaft to operate the grinding burs. Over the hopper 4 is a plate 6 pivoted to the top of the hopper 4 or top of the back of the mill and terminates at one end in a ball 7. To this plate 25 is secured by side pieces 8 over the hopper 4, a sieve or screen 10.

For the purpose of adjusting the screen 10 to a greater or less angle with reference to the top of the hopper 4, the pivot 12 on which the screen vibrates or 30 turns, is provided with a shoulder 14 and on this shoulder rests a washer 15 and the base of the pivot pin is secured to the rear end of the hopper 4 with a nut 16 at the top. By this mode of construction, when the nut 16 is left loose, the forward end of the screen will 35 drop down on the front end of the hopper 4 which is lower than the plane of the screen by the thickness of the plate 6, as shown in Fig. 2, and when the nut is tightened, it will be raised above, to the plane of the top of the plate 6. In this manner the screen can be 40 adjusted to the desired angle to meet the demands of the different size of the grain and regulate the feed into the hopper.

Over the screen is placed a hopper 20. This hopper 45 may be attached to the sides of the mill or to the lower hopper.

In the rear of the hopper 4 is an opening 22 and around this opening is secured an air box 24 which terminates in an inclosed passage 25 connected to a fan in a casing 26. This fan may be operated in any well-known 50 manner by a belt passing over the pulley 28 fixed upon a shaft 30 which rotates the fan.

For the purpose of operating the screen and imparting to it a reciprocating or vibrating motion, the shaft which carries the wheel 5 and operates the grinding 55 burs, extends out beyond the wheel 5. To this is at-

tached a wheel 34 and to the side of this wheel at one side of the center is secured a crank 35 to which a pitman 36 is attached. This pitman is formed into a socket 38 at its other end and engages the knob or ball 7 on the plate 6, forming a ball and socket joint. To 60 the side of the hopper 4 is secured an arm 40 which extends out and is provided with a slot 42 in which the plate 6 is vibrated and by means of which the plate is held steady or in the same plane while it vibrates.

The mode of operating my device is substantially as 65 follows:—The shaft 32 is rotated by its attachment with the power and this rotates the wheel 5 and with it the wheel 34. As the wheel 34 rotates, it operates the pitman 36 and as the pitman 36 is attached to one side of the wheel 34, at each rotation, the pitman will 70 reciprocate the plate 6 in the slot 42 and as the plate 6 is pivoted at its center, it will reciprocate upon its pivot the forward end of the screen 10, and the grain will pass through the screen 10 and into the hopper 4, but the larger substance like stone, will not pass 75 through the screen, but will be shaken off over the end of the screen.

When the grain to be sifted or ground is finer, the forward end of the screen is released by releasing the nut 16 and allowing the screen to drop down nearly to 80 the top of the hopper 4 and by tightening the nut, the screen may be maintained at nearly a horizontal plane, just enough pitch to it to carry off all of that which cannot pass through the meshes of the screen.

It will be noticed that the screen 10, by its position 85 and attachment to the plate 6, will so control the feed into the hopper 4, that there will be a uniform feed from all parts of the screen and the grinding burs will never become clogged or overfed.

When it is desired to take out all of the sand and dust 90 before it is passed into the grinding machine, the fan in the rear in the casing 26 is set in motion and the air is driven along the tube 25 through the opening 22 and underneath the screen 10 and forces all of the dirt and dust out underneath the screen and over the hopper 4. 95

It will be seen that, by this mode of construction, no stones, nails, and the like, will be allowed to pass into the grinding mechanism and injure it, nor will there be any dust or dirt to injure the meal or flour when ground, and all of the parts are adjustably secured together whereby it may be adapted for use with grain of different size and different degrees of cleanliness, and the uniformity of the feed to the grinding mechanism will insure uniformity of product.

Having now described my invention, what I claim 105 and desire to secure by Letters Patent is,

1. In a device of the character described, the combination with a hopper, of a screen, a pivot pin on one end of the hopper, a shoulder on said pivot pin disposed in a plane above the hopper, said screen disposed above the 110 hopper and pivotally supported or laterally oscillation on

the said pivot pin, and a nut threaded on the upper end of the pivot pin for vertical movement thereon and engaging the said screen for regulating the dip thereof.

2. In a device of the character described, upper and 5 lower hoppers, a vertical pin provided on the lower hopper, a screen pivotally supported on said pin for lateral oscillation between the hoppers, and a nut threaded on said pin for regulating the dip of the screen.

3. In a device of the character described, the combination 10 with a hopper provided centrally of one of its ends

with a vertically projecting pin, a screen pivoted centrally of one of its ends on and supported by said pin, and means movable on said pin for regulating the dip of the screen.

In testimony whereof I affix my signature in presence of two witnesses.

JOHN H. FELDERMAN.
